(57) **CLAIM**

The ornamental design for a curling iron face protection mask, as shown and described.

DESCRIPTION

FIG. 1 is a front elevation view curling iron face protection mask.

FIG. 2 is a back elevation view curling iron face protection mask.

FIG. 3 is a top elevation view curling iron face protection mask.

FIG. 4 is a bottom elevation view curling iron face protection mask.

FIG. 5 is a right side elevation view curling iron face protection mask.

FIG. 6 is a left side elevation view curling iron face protection mask; and,

FIG. 7 is perspective view of the curling iron face protection mask worn by a user.

The broken lines in FIG. 7 depict portions of the curling iron face protection mask that form no part of the claimed design.
